UNITED STATES PATENT OFFICE.

GEORGE M. HUBBARD, OF NEW HAVEN, CONNECTICUT, ASSIGNOR TO
W. & E. T. FITCH, OF SAME PLACE.

DESIGN FOR A CLASP FOR BELTS.

SPECIFICATION forming part of Design No. 21,062, dated September 22, 1891.

Application filed August 31, 1891. Serial No. 404,344. Term of patent 7 years.

To all whom it may concern:

Be it known that I, GEORGE M. HUBBARD, of New Haven, in the county of New Haven and State of Connecticut, have invented a new Design for a Clasp for Belts, (Case A;) and I do hereby declare the following, when taken in connection with accompanying drawings and the letters of reference marked thereon, to be a full, clear, and exact description of the same, and which said drawings constitute part of this specification, and represent, in—

Figure 1, a face view of the two parts engaged; Fig. 2, a face view of the eye part; Fig. 3, a face view of the hook part.

This invention relates to a design for a clasp for body-belts, with special reference to the hook-and-eye portions of the clasps; and the design consists in the configuration, as shown in the accompanying illustration and hereinafter described.

A represents the buckle of the eye part, and B the buckle of the hook part. From the eye part the eye projects, representing a bridle-bit cheek, a representing the bar, and b the ring. From the hook part is a projection representing a horseshoe c as the hook, and when the two are together, as in Fig. 1, they present the appearance of a combined horseshoe and bit-cheek, as shown in the accompanying illustrations.

I claim—

The design for a clasp for belts, as described, and shown in the accompanying illustrations.

In testimony whereof I have signed this specification in the presence of two subscribing witnesses.

GEORGE M. HUBBARD.
